UNITED STATES PATENT OFFICE.

DAVID L. CROFT, OF SPRINGFIELD, OHIO.

BLACKBOARD-ERASER.

SPECIFICATION forming part of Letters Patent No. 274,566, dated March 27, 1883.

Application filed June 16, 1882. (No model.)

To all whom it may concern:

Be it known that I, DAVID L. CROFT, of Springfield, in the county of Clarke and State of Ohio, have invented certain Improvements 5 in Blackboard-Erasers, of which the following is a specification.

My invention relates to blackboard-erasers; and it consists in a novel manner of applying the facing or rubbing material to the block, 10 whereby the cost is reduced and all tacks or other projecting fastenings are dispensed with.

In the accompanying drawings, Figure 1 represents a perspective view of my improved 15 eraser; Fig. 2, a perspective view of the facing or rubbing material and its pasteboard form or filling; and Fig. 3 is a vertical cross-section.

The object of my invention is to avoid the use of tacks and at the same time permit the facing material to project slightly past the 20 edges of the block, and to be used, in connection with a filling, the same as when tacked to the block. To this end I adopt the construction shown in the drawings, in which—

A represents the block or body to which the 25 rubbing material B is secured, the block being formed, as usual, with a rib, a, which affords a convenient hold for the hand. The rubbing material B, which is preferably corduroy, is laid upon a thin form, C, of pasteboard or like 30 material, of a size corresponding closely to the face of the block A, the material being turned over upon the back of the form C and cut out at the corners, so that the overturned portions form a series of miter-joints, thus causing the 35 material to lie flat and even thereon. A suitable filling, D, of cotton-batting or other soft and elastic material, is interposed between the face of the thin form C and the rubbing material to give proper elasticity to the eraser, and

the overturned edges or flaps b are then glued, 40 pasted, or cemented to the back of the form C, after which the form, with the covering applied and secured thereto, is glued or cemented to the face of block A, thereby completing the eraser. It will be seen that by this construction no projection of any kind is produced which might injure the surface of the board. The form C, being of the same size as the block, causes the covering material B to project slightly beyond the edge of the block all around, 50 and thus to prevent the block from coming into contact with the board.

I am aware that felt has been secured to the face of a block or body by cement, and that various materials have been turned over the 55 edges of a block or wooden core and clamped between said core and a handle-piece or backing, the wooden core and backing being united by screws or a T-shaped tenon of one part sliding into a corresponding groove in the other 60 part, and I do not claim either of said constructions.

Having thus described my invention, what I claim is—

1. The herein-described eraser, consisting of 65 body A and rubbing material B, folded over the edges of a thin form, C, and cemented thereto, and also cemented to the block.
2. The herein-described eraser, consisting of 70 block A, rubbing material B, and thin form C, the rubbing material being folded over the edges of the form, cut out at the corners to lie flat thereon, and cemented to the form and to the block A, all as shown and described.

DAVID L. CROFT.
